New York

Application April 7, 1951, Serial No. 14,744

Term of patent 14 years

(Cl. D62—4)

To all whom it may concern:

Be it known that we, Walter Dorwin Teague and Robert H. Ensign, citizens of the United States, residing respectively at Annandale, in the county of Hunterdon, State of New Jersey, and at Bronxville, in the county of Westchester, State of New York, have invented a new, original, and ornamental Design for a Cabinet for an Air Conditioning Unit or Similar Article, of which the following is a specification, reference being had to the accompanying drawing, forming a part thereof.

In the drawing, Fig. 1 is a perspective view of a cabinet for an air conditioning unit or similar article embodying our new design; Fig. 2 is an end elevation of the cabinet shown in Fig. 1; and Fig. 3 is a fragmentary perspective view on a reduced scale taken from a position below the cabinet. The opposite end wall of the cabinet is the same as the one appearing in the drawing.

The dominant features of our design are shown in the full-line portions of the drawing.

We claim:

The ornamental design for a cabinet for an air conditioning unit or similar article, substantially as shown and described.

WALTER DORWIN TEAGUE.
ROBERT H. ENSIGN.
